SPINNING FRAME

Richard Patterson, Glendale, R. I., assignor to
Stillwater Worsted Mills, a corporation of
Rhode Island

Application February 6, 1941, Serial No. 377,628

16 Claims. (Cl. 19—130)

My invention relates to spinning frames.

It has among its objects to provide improved means for controlling and directing the drafted ends. A further object is to provide such improved means especially adapted to use in connection with pressure mechanism of the type whereby the twisting of the yarn is divorced from the drafting function of the front rolls. Another object of my invention is to provide such improved means adapted to be carried on a concave pressure plate of such a mechanism and which, while in no way interfering with the operation of the latter, also functions to improve the end controlling function of such a plate in such manner as with increased certainty to cause any end resulting from breakage of the yarn to be directed upward and lapped around the top front roll from which it may be readily removed. Still further objects of my invention are to provide an improved lap maker adapted to catch a drafted end escaping from a concave pressure plate and control and direct said end in an improved manner, and, more particularly, to provide such an improved lap maker adapted to form an extension of such a plate and to be carried thereon. These and other objects and advantages of my improvement will, however, hereinafter more fully appear.

In the accompanying drawing, I have shown for purposes of illustration two embodiments which my invention may assume in practice.

In this drawing:

Figure 1 is an end elevation of a spinning frame equipped with my improvements;

Fig. 2 is a front elevation of a portion of the frame;

Fig. 3 is a sectional view on line 3—3 of Figure 1;

Fig. 4 is an enlarged end elevation of my improved structure in operative position;

Fig. 5 is an enlarged plan view of the same as seen on line 5—5 of Figure 4;

Fig. 6 is a detail perspective view showing connection of the lap maker to the supporting plate of Figure 4, and

Fig. 7 is a view similar to Figure 4, of a modified construction.

As illustrated herein, a standard form of spinning frame is shown including a usual carriage stand 1 having usual drafting mechanism including a lower fluted front roll 2 and a suitable top front roll 3, herein cork covered, while a usual pressure frame 4 carries resilient pressure means 5 on its front end and is pivoted at 6 on the front saddle bar 7; my improved lap maker mechanism,

generally indicated at 8, being carried by the pressure means 5 and cooperating therewith and with the top front roll 3 in an improved manner as hereinafter described.

5 The pressure means 5 shown herein is of the resilient type invented by Walter S. Eastman, and is not per se the subject matter of my present invention. However, to facilitate understanding of the latter, it is desirable to note that 10 this pressure means includes a supporting plate 9 having a central hole therein adapted to receive and be seated on an upstanding ball 10 on the front end of the pressure frame 4 to provide a universal joint, while an upper resilient pressure plate 11 has depending edges 12 receiving and supporting the plate 9, and upturned ends 13 on the latter support the pressure plate 13 at the opposite ends, as usual in such devices. Thus, 15 the drafted yarn passing out between the nip of the drafting rolls 2 and 3 is supported on the plate 11, which, when pressed upward by the pressure frame 4, is flexed and conforms to the bottom of the top roll 3 while the twisting begins after the yarn is free from pressure and as it 20 passes off the enlarged front edge 12 of the plate 11 downward to a usual closed pigtail guide 14 disposed above the caps 15 of usual whirl bobbins 16, all in the manner usual in such Eastman devices.

30 In my improved construction, the supporting member 9 carries my improved lap maker mechanism 8. As shown, the latter includes an elongated body 17 of substantially the width of the roll 3 and of the supporting member 9 and transversely shallowly corrugated while conforming generally to the periphery of the top roll 3. Herein, the inner edge 18 of this member is parallel to and spaced in front of the enlarged curved front edge of the pressure plate 11. To maintain this relation while still providing for the support of the member 17 on the supporting member 9, a laterally and longitudinally disposed flat extension 19 is provided on the member 17 adjacent its edge 18 and the free end of 35 this extension is extended laterally in parallel spaced relation to the edge 18. A portion 20 is accordingly provided which is adapted to overlie the plate 9 adjacent the front upward extension 13 thereon and to be suitably fixed to the plate 9 as, for example, by rivets 21. Thus, without interfering with the operation of the pressure plate 11, the member 17 is supported in the desired spaced relation and caused to be disposed with its corrugated surface forming an extension 40 of the pressure plate 11 and extending a sub-

stantial distance beyond the latter upward and around the roll 3 in proximity thereto and generally conforming to the periphery thereof, although in spaced relation from the latter.

In the operation of my improved mechanism, it will be evident that should an end break and not be directed against and lapped on the roll 3 by the pressure plate 11, the end will be directed by the roll 3 between the latter and the member 17. As a result of the engagement of the yarn with this corrugated member, the yarn is either immediately deflected by one of the corrugations into contact with the periphery of the roll 3, or caused to bunch in the space between the member 17 and the roll 3 until the latter can engage a portion of the bunched yarn and start to lap the same around the roll. Obviously this lapping, once started, will continue and the lapped yarn may be readily removed by the operator.

As a result of my improvement, it is found that the troubles heretofore experienced when an end does break and get away from the concave plate 11, and shoot out of the same into the alley or cross over to the next end in such manner as thereby to cause more broken ends, are effectively overcome. Further, it will be noted that this mechanism may be applied to the pressure mechanism with facility, and that the same is inexpensive and does not in any way interfere with the normal operation of the pressure mechanism. Also, it will be evident that my improvement is capable of being applied to other forms of pressure mechanism of the Eastman type than that illustrated in Figures 1 to 6, the same, for example, also being shown in Figure 7 as applied without change to such a mechanism having a rigid concave plate 22.

While I have in this application specifically described two embodiments which my invention may assume in practice, it will be understood that the same are shown for purposes of illustration, and that the invention may be modified and embodied in various other forms without departing from its spirit or the scope of the appended claims.

What I claim as new and desire to secure by Letters Patent is:

1. In a spinning frame, drafting mechanism including cooperating front rolls, pressure mechanism for pressing the drafted yarn against the top front roll and delivering the yarn for twisting, and means in front of said pressure means for lapping broken ends on said top front roll.

2. In a spinning frame, drafting mechanism including cooperating front rolls, pressure mechanism for pressing the drafted yarn against the top front roll and delivering the yarn for twisting, and means carried by said pressure means for collecting and bunching broken ends in front of said pressure means in the path of said top front roll.

3. In a spinning frame, drafting mechanism including cooperating front rolls, pressure mechanism for pressing the drafted yarn against the top front roll and delivering the yarn for twisting, and lap maker means in front of said pressure means and extending around the top front roll.

4. In a spinning frame, drafting mechanism including cooperating front rolls, pressure mechanism for pressing the drafted yarn against the top front roll and delivering the yarn for twisting, and transversely corrugated lap maker means carried by said pressure means in front

of the latter and spaced from and conforming to the periphery of said top front roll.

5. In a spinning frame, drafting mechanism including cooperating front rolls, pressure means including a pressure plate conforming to the top front roll, and lap maker means carried by said pressure means and in front of said plate and forming an extension thereof.

10 6. In a spinning frame, drafting mechanism including cooperating front rolls, pressure means including a pressure plate conforming to the top front roll, and lap maker means carried by said pressure means and in front of said plate and forming an extension thereof and having a slot between the rear end thereof and the front end of said plate.

20 7. In a spinning frame, drafting mechanism including cooperating front rolls, pressure means for pressing the drafted yarn against the top front roll and having a plate conforming to said roll, and lap maker means carried by said pressure means in front of said plate and forming an extension thereof generally conforming to and spaced from the periphery of said roll.

25 8. In a spinning frame, drafting mechanism including cooperating front rolls, pressure means for pressing the drafted yarn against the top front roll and having a plate conforming to said roll, and transversely corrugated lap maker means carried by said pressure means in front of said plate and forming an extension thereof generally conforming to and spaced from the periphery of said roll.

30 9. In a spinning frame, drafting mechanism including cooperating front rolls, pressure means including a pressure plate conforming to the top front roll, and lap maker means carried by said pressure means and in front of said plate and forming an extension thereof, said pressure plate having a supporting plate beneath the same and said lap maker means having an extension attached to said supporting plate.

40 10. In a spinning frame, drafting mechanism including cooperating front rolls, pressure means including a pressure plate conforming to the top front roll, and lap maker means carried by said pressure means and in front of said plate and forming an extension thereof, said lap maker means having an extension attached to said plate.

50 11. In a pressure mechanism for spinning frames, pressure means for pressing yarn against a roll, and lap maker means carried by said pressure means and forming an extension in front thereof.

60 12. In a pressure mechanism for spinning frames, pressure means for pressing yarn against a roll, and lap maker means carried by said pressure means and forming an extension in front thereof, both said pressure means and lap maker means being curved to conform generally to the periphery of said roll.

65 13. In a pressure mechanism for spinning frames, pressure means for pressing yarn against a roll, and lap maker means carried by said pressure means and forming an extension in front thereof, said lap maker means having transverse corrugations along the same.

70 14. In a pressure mechanism for spinning frames, pressure means for pressing yarn against a roll, and lap maker means carried by said pressure means and forming an extension in front thereof, said pressure means including a pressure plate and an underlying supporting plate

and said lap maker means being attached to one of said plates.

15. In a pressure mechanism for spinning frames, pressure means, and lap maker means carried thereby and forming an extension in 5 front thereof, said pressure means including a concave plate and said lap maker means being carried by said plate.

16. A lap maker for yarn supporting and pressing means for spinning frames comprising an elongated generally arcuate and transversely corrugated member having a transverse slot in one end thereof and a connecting portion along said slot.

RICHARD PATTERSON.
